(57) **CLAIM**

The ornamental design for a convex array ultrasonic probe,
as shown and described.

DESCRIPTION

FIG. 1 is a perspective view of a convex array ultrasonic probe;

FIG. 2 is a front view of the convex array ultrasonic probe;

FIG. 3 is a rear view of the convex array ultrasonic probe;

FIG. 4 is a left side view of the convex array ultrasonic probe;

FIG. 5 is a right side view of the convex array ultrasonic probe;

FIG. 6 is a top view of the convex array ultrasonic probe;

FIG. 7 is a bottom view of the convex array ultrasonic probe;

FIG. 8 is an enlarged perspective view of detail 8 circumscribed within FIG. 1;

FIG. 9 is an enlarged view of detail 9 circumscribed within FIG. 7; and,

FIG. 10 is an enlarged view of detail 10 circumscribed within FIG. 7.

The broken lines in the drawings depict portions of the
convex array ultrasonic probe that form no part of the
claimed design.
